Application August 21, 1934, Serial No. 740,758

10 Claims. (Cl. 229—34)

This invention relates to improvements in containers of the type formed up from a single blank of foldable material such as fiber, cardboard, corrugated cardboard, pressboard, and the like.

5 The general object of this invention is to provide containers of such materials from a single piece blank folded up so that all of the exposed edges of the containers are finished and all joints are flush.

10 These and many other objects as will appear from the following disclosure are secured by means of this invention.

This invention resides substantially in the combination, construction, arrangement and relative 15 location of parts, all as will be apparent more fully from the following description.

In the drawings,

Figure 1 is a perspective view of one form of container in accordance with this invention having sides lower than the ends;

20 Figure 2 is a perspective view of the same container in partially folded condition;

Figure 3 is a plan view of the blank from which this container is formed;

25 Figures 4 and 5 are perspective views of a modified form of container showing the blanks only partially folded;

Figure 6 is a perspective view of another form of container having the sides of the same height as the ends;

30 Figure 7 is a perspective view of this container showing the blank partially folded; and

Figure 8 is a perspective view of a further modified form of container showing the blank 35 partially folded.

Filing containers comprising cases having slide- 40 able drawers are now frequently made of a manu-
ally foldable material, such as cardboard, corrugated cardboard, fiber, pressboard, and the like.

45 Such filing cabinets are relatively inexpensive and are sufficiently rugged to make them available for filing away papers and other materials which must be readily available and yet seldom referred to.

50 The present invention is related to the drawer of such filing cabinets although the containers of the invention are, of course, not limited to such uses. An important object of the invention is the forming of the drawer from a single piece blank previously scored or creased so that any one may readily fold the blank up into a strong, rigid drawer or container. Since such drawers are often made of relatively thick corrugated cardboard, it is desirable to have the exposed 55 edges of the completed drawer or container fin-

ished. The raw or cut edge of corrugated cardboard is rather unsightly, and one of the objects of this invention is to so form and fold the blank that none of the raw edges of the blank are exposed. Furthermore, in accordance with this 5 object the blanks of this invention are so folded that all outside faces of the container are smooth and flush or, in other words, none of the edges of the blank project above the sides of the container at any point.

10 The container of Figures 1-3, inclusive, is of the type in which the sides are lower than the ends, which is often desirable in a filing cabinet drawer. The blank of the container of Figure 1 is illustrated in Figure 3. It is cut from a single 15 piece of material which is of generally rectangular form and provided with scored or creased lines which define the lines of fold. In the drawings, all edges of the blank are shown in solid lines and all score, crease or fold lines are 20 shown by dotted lines.

15 The finished blank comprises a central portion 1 which is the bottom of the drawer. It is defined by the fold lines 2, 3, 4 and 5. At 6 and 7 are the side extensions of the bottom from which 25 the sides of the drawer are formed. At 8 and 9 are the fold lines which extend between the apices of the notched ends 10 of the side extensions. The outer ends of the sides 6 and 7 are provided with the tabs 11 and 12. The ends of the bottom 30 have integral tabs which consist of the portions 13 and 21 and 17 and 25, respectively. The portion 13 is defined by the fold lines 2, 14, 15 and 16. The portion 21 is defined by the fold lines 14, 23, and 24. The flap 28 is defined by the fold line 35 22 and the slots 29. The portion 11 is defined by the fold lines 4, 18, 19 and 20. The portion 25 is defined by the fold lines 18, 26, and 27. The flap 30 is defined by the fold line 30' and the slots 31. The portions 13 and 21 and 17 and 25 form the 40 high ends of the drawer, the portions 13 and 17 forming the outer walls of the end and the portions 21 to 28 and 25 to 30 forming the inner walls thereof. The end wall parts are provided with side extensions comprising the parts 50 and 45 51 separated by the cut or slot 52, portions 53 and 54 separated by the slot 55, portions 32 and 33 separated by the slot 34, and the portions 35 and 36 separated by the slot 37. The part 33 is notched at 39 and provided with a fold line 43, 50 the portion 36 is notched at 41 and provided with a fold line 45, the portion 50 is notched at 56 and provided with a fold line 60, and the portion 53 is notched at 58 and provided with a fold line 66. The portions 32 and 51 and 35 and 54 55

are separated by the side wall flaps 6 and 7, respectively, by a cutter slot that will be apparent from the figure.

This blank is folded up as indicated in Figure 5 to form the drawer or container of Figure 1. Each end of the blank is folded over along the fold lines 14 and 18 so that the portions 33, 25 and 36 overlie the portions 32, 17 and 35, respectively, at one end and the corresponding parts 10 overlie at the other end. At each corner the portions 33, 36, 50 and 53 are folded on the lines 43, 45, 60 and 62, respectively, so that the areas 48, 47, 64 and 66 overlie the areas 48, 46, 65 and 67, respectively. The position of the parts at 15 this stage are shown in the lower right hand corner of Figure 2. The portions 32, 35, 51 and 54 are then folded along the fold lines 42, 44, 61 and 63, respectively. The extensions of the parts 32, 35, 51 and 54 then overlie the extensions of the 20 parts 33, 36, 50 and 53, respectively. This will be clear from Figure 2 by observing the upper right hand corner of the container. The extensions at the end walls are then folded up at right angles to the end wall, as indicated at the 25 upper right hand corner of Figure 2. The end walls are then folded up at right angles to the bottom, in which case the pairs of overlying extensions will point towards each other and stand at the side edges of the bottom 1 and at right 30 angles thereto, as is clear from Figure 2. The sides 6 and 7 are then folded up at right angles to the bottom and the upper portions are then folded down along the fold lines 8 and 9, respectively, so as to become parallel and encase the 35 extensions of the end walls. The flaps 28 and 30 are then folded up on the fold lines 22 and 30', respectively, so that the tabs 11 may contact with the inner faces of the portions 13 and 17 of the end walls. The flaps are then folded back 40 into place, as is clear from Figure 1. The container is now completely assembled with the parts locked in folded position.

An important feature aside from rigidity and ruggedness of a construction of this type is found 45 in the fact that all of the exposed edges 8, 61, 14, 63, 9, 44, 18 and 42 (Figure 1) are finished edges and at no place are the raw edges of the material exposed. Furthermore, the joints at A on the sides of the container are abutting so 50 that the side faces of the container are entirely flush.

In the description of the modification shown in Figure 4, only the parts at one end will be numbered and discussed since the other end is a 55 duplicate, and in fact this same procedure will be followed out with all the remaining forms illustrated. In the modification of Figure 4 the container is again made from a one piece blank. It is cut from a rectangular piece along the outline 60 indicated by solid lines and is provided with fold lines, as indicated by the dotted lines of the drawings. The bottom is shown at 70 and the side wall at 71 and 72. The end walls consist of the portions 73, 74, 75, 77, 78 and 79. The parts 75 65 and 77 and 78 and 79 are separated by the cut or slot 76 and 80, respectively. The end wall is formed by folding the flap along the dotted and cut lines so that the portion 74 overlies the portion 73, the portion 77 overlies the portion 75, and the portion 79 overlies the portion 78. The overlying portions 75 and 76 are then folded along 70 the fold lines 81 and 82 which are coincident, and likewise the portions 79 and 78 are folded along the overlying fold lines 84 and 83. These double fold portions are then folded up at right angles

to the double thickness end walls comprising the portions 73 and 74, which in turn are then folded up so as to stand at right angles to the bottom 70.

The side walls 71 and 72 are then folded up at right angles to the bottom and then down over the extending portions of the end walls. These extending portions of the end walls assume a position which is clear from the lower left hand corner of Figure 4. The flaps on the inner walls of the end walls are then folded up so that the 10 extensions of the side walls can be locked thereunder.

It will be clear from Figure 5 as to the shape of the blank. The extensions at the end of the bottom walls are folded upon themselves so that 15 the parts 88 and 87 and 90 and 89 overlie. The parts 89 are then folded along the crease lines 91. The double fold extensions at the sides of the end walls are then bent up at right angles to the end walls, which in turn are bent up at 20 right angles to the bottom, as is clear from Figure 5. The side walls 85 and 86 are then bent up at right angles to the bottom and down over the double fold extensions where they are in this case glued in place to form the finished container. 25 This container, as well as that of Figure 4, has finished exposed edges and flat or flush outside faces.

The container of Figures 6 and 7 differs from those previously described in that the side walls 30 are of the same height as the end walls. The blank is partially folded as shown in Figure 7. To form the container from this blank the portion 97-100 is folded along the line 98 so that 35 97 overlies 96. This double fold part is now folded along the line 99 so that the flat contacting parts 96 and 97 move parallel to and in engagement with the portion 95. This gives a triple 40 thickness end wall. The extension beyond the triple thickness formed by the portions 95, 96 and 97 are then bent up at right angles to the plane thereof. The triple thickness end wall is then bent up at right angles to the bottom 92. The extensions at the sides of the end wall then 45 assume the position shown at the left hand end of Figure 7. The side walls 93 are then bent up and over so as to encase this extension. The notches 103 are provided so that the tabs 102 at the end of the side wall will snap thereinto and lock the parts in place. Here again all exposed 50 edges are finished and the outer faces of the side walls are flush.

The shape of the blank of the structure of Figure 8 will be clear from the drawings. In this case the portions 114-117 are folded along the 55 line 116 so that 114 overlies 113 and 117 overlies 118. This double thickness portion is then folded along the line 115 so that the areas 114, 113 and 112 are all parallel and in contact, forming a triple thickness end. The extension at the side 60 edges of the triple thickness end are then bent up at right angles thereto and the end wall in turn bent up at right angles to the bottom 110. The position of the parts is clear from the left hand end of Figure 8. The side walls 111 are then bent 65 over the extensions and glued in place so as to encase the extensions and lock the parts together. Here again all exposed edges are finished and the outer faces of the side walls are flat.

From the above description it will be apparent 70 that this invention resides in certain principles of construction and assembly which as will be clear to those skilled in the art may be varied without departure from the scope of the inven- 75

tion. We do not, therefore, desire to be strictly limited to the disclosure as given for purposes of illustration but rather to the scope of the appended claims.

What we seek to secure by United States Letters Patent is:

1. A container of the type described folded from a single piece of material, comprising a bottom wall and end and side walls of double thickness formed by folding the material thereof into parallel overlying portions whereby all the top edges of the container are finished, the side walls being lower than the end walls and the end walls having integral extensions lying between the parallel portions of the side walls and defined by an edge which extends from the level of the side walls to the upper edges of the end walls, the extensions being formed by flaps one enfolding the other.

2. A container of the type described, comprising a bottom, side and end walls, the side and end walls having extensions folded down into the container so as to lie parallel thereto, the side edges of the end walls having extensions partially lying between the inner and outer portions of the side walls, those portions of the extensions not lying between the side walls being of sufficient thickness to form a flush sided container.

3. In a box of foldable material, the corner construction comprising an outer thickness of end wall extension enfolding a portion of an interior extension, the remaining portion of said interior extension being embraced by the enfolding side wall, the outer thickness of said side wall meeting the outer thickness of said end wall extension in a flush abutting seam angularly displaced from the vertical corner.

4. A corner of an open ended tray of foldable material including a bottom, and side and end walls of inner and outer thicknesses, with the outer thickness of end wall portion, extending around the vertical corner to meet in abutting relationship in the same plane with the outer thickness of side wall along a line substantially displaced from the corner, with open end edges of said end and side walls formed by folding.

5. A tray as described comprising bottom, side and end walls with all top edges folded and with junction of side and end walls extending along a line at an angle to the vertical corners, said side and end walls lying in the same plane at said junction.

6. A container as described, comprising a bottom wall, double thickness side walls, and end

walls having pairs of extensions enfolded by the double thickness side walls, one extension of each pair being folded over the other.

7. In an open ended box of foldable material having double thickness side and end walls formed by infolded extensions of the outer thickness, the corner construction as described comprising an end wall extension arranged to lie within the thicknesses of the coating side wall, interior corner locking means on the infolded side wall extensions, said locking means being engaged at its free end by the infolded end wall extension abutting the outer thickness of side wall extension and lying in the same plane therewith.

8. A container of the type described comprising a bottom wall, double thickness end and side walls all formed from a single piece of material and having the side walls lower than the end walls, the end walls having a pair of integral extensions at each side, said extensions partially lying between the inner and outer portions of the side walls, the exposed portions of the extensions having at least three thicknesses formed by folding one extension of each pair over the other extension of that pair.

9. A container of the type described comprising a single blank of material folded to form a bottom wall, double thickness end walls and double thickness side walls, the side walls being lower than the end walls, said end walls having integral extensions at the sides of the same height as the height of the end walls at their point of attachment thereto and of decreasing height down to the top edges of the side walls and terminating in portions lying between the side walls, all of the top edges of the container being smooth, and portions of the extensions meeting the sides in abutting relation to provide smooth sides for the container.

10. A container of the type described comprising a bottom, side and end walls, the side and end walls having extensions folded down into the container so as to lie parallel thereto and form double thickness walls, the side edges of the end walls also having extensions the terminal portions of which are of less thickness than the initial portions, the terminal portions lying between the inner and outer portions of the side walls, and the initial portions abutting against the outer portions of the side walls to form a container having smooth outer side faces.

SAMUEL A. WOOD.
FRANK D. JONAS.
